Filed Mar. 13, 1961, Ser. No. 64,244

Term of patent 14 years

(Cl. D81—10)

FIG. 1 is an end view of an electric heater, showing our new design;

FIG. 2 is a side view;

FIG. 3 is a rear elevational view;

FIG. 4 is a front elevational view thereof; and

FIG. 5 is a sectional view taken along line 5—5 of FIG. 4 in the direction of the arrows.

The spaced lines on the arcuate panels at each side of the heater front as seen in FIGS. 2 and 4 indicate a surface pattern.

The characteristic features of our design for the electric heater disclosed reside in the specific overall configuration of the housing and the wire grillework, as best illustrated in FIGS. 1 and 4 respectively.

We claim:

The ornamental design for an electric heater, substantially as shown and described.
